CLAIM

The ornamental design for a carriage sit box for reformer exercise apparatus, as shown and described herein.

DESCRIPTION

FIG. 1 is an upper perspective view of my new carriage sit box design.

FIG. 2 is a right side elevational view of my new carriage sit box design.

FIG. 3 is a left side elevational view of my new carriage sit box design.

FIG. 4 is a head end elevational view of my new carriage sit box design shown in FIG. 1.

FIG. 5 is a foot end elevational view of my new carriage sit box shown in FIG. 1.

FIG. 6 is a top plan view of my new carriage sit box design; and,

FIG. 7 is a bottom plan view of my new carriage sit box. The broken line showing of portions of the carriage sit box for reformer exercise apparatus forms no part of the claim.
